ELECTRIC LAMP WITH UNITARY INNER ENVELOPE AND STEM ASSEMBLY AND MANUFACTURE THEREOF

George K. Danko, Chesterland, Ohio, assignor to General Electric Company, a corporation of New York
Filed June 18, 1962, Ser. No. 203,237
1 Claim. (Cl. 316—20)

This invention relates to electric lamps and to methods of manufacture thereof.

It is a principal object of the invention to provide a novel lamp structure incorporating a light source enclosed in a compact inner envelope or chamber which is enclosed in a larger outer bulb or envelope. It is a further object to provide such a structure capable of assembly and manufacture on high-speed, automatic equipment, and therefore adaptable to production in high volume at relatively low cost. It is a still further object to provide a structure of the type described adaptable for use in conventional sockets and fixtures for general lighting purposes.

In recent years there has been introduced on the market an incandescent filament lamp having a high efficiency for a long useful life with virtual freedom from blackening, all made possible by operating a tungsten filament in a compact bulb containing, in addition to the usual gas filling, a quantity of halogen which serves as a regenerative getter. During operation of the lamp, the walls of the compact bulb are heated to a uniformly high temperature, and tungsten vapors normally volatilized from the filament at its high operating temperature and deposited on the bulb walls, combine chemically with the halogen to form a tungsten-halogen compound which migrates to the vicinity of the hot filament where it is dissociated to release tungsten which redeposits on the filament, the halogen returning to the bulb walls to combine with further quantities of tungsten deposited thereon, thereby repeating the cycle. Particularly good results have been obtained in lamps employing iodine as the regenerative getter as disclosed and claimed in Patent 2,883,571, Fridrich et al., which is assigned to the same assignee as the present application.

In order to achieve and maintain proper operating conditions, including temperature and spacing between bulb wall and filament, for effective functioning of the tungsten-halogen cycle, the enclosing envelope or bulb must be of compact size. It has also been the practice to make such lamps in a double-ended construction wherein the lead-in conductors extend into opposite ends of the small tubular envelope with the filament extending axially through the length of the envelope. Such a structure requires special bases or terminals and is evidently not adaptable for use in the sockets and fixtures for general purpose lamps which comprise a relatively large bulb having a neck portion to which is attached a base, conventionally a screw-threaded base. It is therefore a particular object to make available the advantages of high efficiency and long life of the tungsten-halogen principle in a lamp having the physical or structural characteristics of a general lighting lamp.

In accordance with one aspect of the invention, the above-stated objects are achieved in a structure wherein the lamp comprises an outer glass bulb or envelope having a neck portion and which may be of a size and shape such as those employed in general service lighting lamps for ordinary household or commercial or industrial applications. A re-entrant inner envelope extends into the interior of the outer bulb and has a closed inner end and an open outer end sealed to the neck portion of the outer bulb. The said inner envelope has, intermediate its inner and outer ends, a seal portion whereat the walls of the envelope are collapsed or compressed to form a hermetic

seal to define a sealed inner chamber between the said seal portion and the closed inner end of the inner envelope. The light source, preferably a tungsten filament, is located within the said inner chamber and is electrically connected at its ends to respective lead-in conductors which have portions thereof hermetically sealed in said seal portion and which extend outwardly through the open outer end of said inner envelope.

In accordance with a further aspect of the invention, the assembly of inner envelope, filament and lead-in wires is consolidated into a unit, or inner assembly, prior to insertion of that assembly into the outer bulb. Also in accordance with a preferred aspect of the invention, that assembly further includes a glass exhaust tube which extends into the interior of the inner envelope through its open end. During formation of the said seal portion of the inner envelope, the softened walls of the inner envelope are preferably compressed around the inner end of the exhaust tube and sealed thereto without closing off the passage through the interior of the exhaust tube. The said inner chamber portion of the inner envelope is then evacuated and filled with the desired atmosphere through the said exhaust tube. The said inner chamber is then closed off preferably by reheating a localized portion of the walls of the seal portion and collapsing or compressing those walls to seal off the opening in the exhaust tube. Another localized portion of a wall of the seal portion may then be pierced to form an exhaust aperture communicating with the interior of the exhaust tube to enable subsequent exhausting and gas filling of the outer bulb.

The lamps may then be completed by attachment of a conventional base to the neck portion of the outer bulb and attachment of the lead-in conductors to the base contacts or terminals.

Further features and advantages of the invention will appear from the following detailed description taken in conjunction with the drawing, wherein:

FIG. 1 is an elevation, partly in section, of a lamp embodying the invention;

FIGS. 2 to 10 illustrate various steps in the assembly and fabrication of the lamp; and

FIG. 11 is an elevation, in section, showing an intermediate stage in the manufacture of the lamp in accordance with a modified procedure.

Referring to FIG. 1 of the drawing, the lamp illustrated therein comprises an outer glass bulb 1 having a neck portion 2 and which may be evacuated or filled with a suitable gas such as nitrogen. The bulb 1 contains an internal assembly including a re-entrant inner glass envelope 3 having a closed inner (upper) end 4 and an open outer (lower) end 5 which is flared outwardly and is sealed by fusion at 6 to the neck 2 of the outer bulb. The inner envelope 3 has, intermediate its ends, a seal portion 7 whereat the walls of the envelope 3 are fused and collapsed or compressed to form a hermetic seal thereby constituting the upper portion of the envelope 3 a hermetically sealed chamber 8. The chamber portion 8 of inner envelope 3 contains a filament 9, preferably a coiled or coiled-coil tungsten filament extending axially of the chamber 3. The filament 9 is connected at its ends to respective longer and shorter lead-in wires 10 and 11 which have portions thereof hermetically sealed in the seal portion 7 and extend longitudinally therethrough and outwardly through the open end of the inner envelope 3.

The internal assembly also preferably includes a glass exhaust tube 12 extending into the interior of envelope 3 and having a portion thereof at its inner (upper) end embedded in the seal portion 7. As explained more fully hereinafter, during initial manufacture of the internal assembly the exhaust tube 12 has its interior open through the seal 7 into the chamber 8 for the purpose of evacuating and filling the chamber with a desired atmosphere.

However, in the completed lamp the exhaust tube 12 is sealed off as shown at 13 in FIG. 9, but it is in communication with the interior of the outer bulb 1 through an exhaust aperture 14 in a wall of the seal 7, the outer end of exhaust tube 12 being sealed and tipped off at 15.

The filament 9 may be additionally supported by a supplemental support wire 16 (see FIG. 5) which has one end embedded in a button portion 17 at the upper end of the exhaust tube 12 and its other end formed into a loop encircling the filament 9 at its midpoint.

The bulb 1 has attached thereto a base 18 which may be a conventional screw thread base comprising a screw-threaded sheet metal shell 19 cemented to the bulb neck. The lead wires 10 and 11 are connected, respectively, to an end or center contact 20 and to the shell 19.

The inner chamber 8 containing the tungsten filament 9 preferably constitutes a compact high intensity incandescent lamp of the type operating with a halogen regenerative cycle, preferably a tungsten-iodine cycle as described and claimed in the aforesaid Patent 2,883,571. To that end, the chamber 8 contains an inert gas filling such as nitrogen, argon, krypton or xenon or mixtures thereof at a pressure of preferably at least several hundred millimeters of mercury or even exceeding atmospheric pressure. Additionally, the chamber 8 contains a small quantity of iodine which, during operation of the lamp, maintains the walls of the chamber free from deposits of tungsten vaporized from the filament 9. In view of the requisite relatively high operating temperature, wherein the walls of the chamber 8 attain a temperature in excess of 250° C., for example approximately 500° C., the envelope 3 is made of glass having a relatively high softening point, such as one of the well known so-called hard glasses like borosilicate or alumino-silicate glasses, or quartz glass. The outer bulb 1 is preferably made of a compatible glass. The lead wires 10 and 11 are preferably of tungsten which forms a hermetic seal with such glasses which have a low coefficient of expansion. However, when desired, the outer portions of the lead wires 10 and 11 located below and outside the seal area 7 may be made of other metal such as copper or nickel.

It will be evident that the outer bulb 1 may be of a size and shape like that of conventional household lamp bulbs, and it may be provided with a frosted or diffusing coating or a metallic reflecting coating. The filament 9 may be of any desired capacity such as, for example, about 150 watts or more for operation from conventional power supply sources of about 110 or 220 volts. Thereby, as compared to conventional household lamps operating at, for example, about 16 lumens per watt for 750 hours in the popular 100 watt size, lamps of the halogen cycle type may be operated at efficiencies of, for example, 20 to 25 lumens per watt for a life in excess of 2000 hours and with virtually no depreciation in light output during life.

In accordance with a further aspect of the invention, the assembly and manufacture of the lamp may be carried out substantially as follows. In the first step, illustrated in FIG. 2, the upper end of the exhaust tube 12 is heated and upset to form the button 17, and one end of a straight length of support wire 16, preferably of tungsten, is inserted into the softened button 17. During this operation the exhaust tube 12 may be supported in a support member or spindle 21 as shown somewhat diagrammatically in FIG. 3, the said holder 21 being one of a number of such holders carried at the periphery of the indexing turret of a mount making machine similar to those well known in the art. The exhaust tube is loaded into an axial passage 22 in the holder 21 with its bottom engaging a shoulder 23, the passage being sealed by an O-ring seal 24.

Straight lengths of the lead wires 10 and 11 are dropped into respective passages 25 and 26 in the holder 21 and come to rest on a shoulder 27. Then the upper ends of the lead wires 10 and 11 are formed to provide laterally

bent portions 28 with hooks in the ends thereof into which are inserted the ends of the filament 9, after which the hooks are clamped to firmly grasp the filament.

In the next step, the support wire 16 is bent to the shape shown in FIG. 5 with a loop in its free end encircling the filament 9 at its midpoint.

Then, as shown in FIG. 6, the glass envelope 3 is dropped over the assembly of filament 9 and the lead wires 10 and 11 with its flanged lower end 5 resting on a shoulder 29 (FIG. 3) on the support member 21. Then a flow of inert or reducing gas, for example nitrogen, is started into the lower end of the exhaust tube 12 by way of a passage 30 (FIG. 3) in the support member 21, in order to protect the filament and other wires inside envelope 3 from oxidation, after which a zone of the envelope 3 adjacent the upper end of the exhaust tube 12 is heated by flames from burners indicated at 31. The burners 31 are actually directed at the envelope 3 in directions at right angles to those shown in FIG. 6, that is, they are located at opposite sides of the plane containing the lead wires 10 and 11. The said zone is heated to its softening point and the walls of the envelope 3 are collapsed and then compressed by a pair of pinch jaws (not shown) to form a seal area 7 (FIGS. 7 and 8) in which are hermetically sealed and embedded portions of the lead wires 10 and 11. The said pinch jaws are relieved or notched at the center in known manner so that the inner walls of envelope 3 in area 7 are fused and hermetically sealed to the outer walls of the exhaust tube 12 without closing the passage through the interior of the exhaust tube.

If desired, the portions of lead wires 10 and 11 which are embedded in the seal 7 may be precoated or beaded with glass in known manner.

The assembly thus formed and shown in FIG. 7, is then removed from the holder 21 (FIG. 3) and transferred to exhaust and gas filling equipment in which it is preferably supported in an inverted position as shown in FIG. 9. The chamber portion 8 of the assembly is then exhausted and filled with the desired gas filling, such as argon and a small quantity of iodine. During the steps of filling with gas and with iodine vapor, the lower end of the chamber 8 is preferably cooled with liquid nitrogen to condense the iodine vapor. Then the chamber 8 is sealed off as shown at 13 in FIG. 9, preferably by locally heating the walls of the seal area 7 with burners indicated at 32 and either permitting the glass to collapse or compressing with pinch jaws to form the seal 13.

Next, an aperture 14 (FIG. 9) is formed in a wall of the seal area 7 at a point spaced from the seal 13 and in communication with the interior of the exhaust tube 12. The aperture 14 is preferably formed by localized heating and softening of the glass with a burner 33 and application of compressed air to the interior of the exhaust tube 12 to blow out the aperture 14.

In the next step, the assembly shown in FIG. 9 may be transferred to a conventional sealing-in machine where an outer glass bulb 1 (FIG. 10) is dropped over the internal assembly of envelope 3 and associated elements, and the neck portion 2 of the bulb is fused and hermetically sealed to the flared end 5 of the envelope 3 to form the seal 6.

The interior of the outer bulb 1 is then evacuated through the exhaust tube 12 by way of aperture 14, and is preferably filled with a desired gas, such as nitrogen at about 600 mm. Hg pressure. The exhaust tube 12 is then tipped off as shown at 15 (FIG. 1), after which the base 18 is mounted on the bulb neck and the lead wires 10 and 11 connected thereto in conventional manner.

In FIG. 11 there is illustrated a modification in the manufacture of the internal assembly. In this case the closed upper end 4 of the envelope 3 is provided with a glass exhaust tubulation 34. Also, during formation of the seal portion 7, it is compressed in a manner to close or seal off the exhaust tube 12, after which it is reheated and the exhaust aperture 14 is blown through the mass

of plastic glass. The chamber 8 is then evacuated and filled with the desired atmosphere through the tubulation 34 which is then sealed or tipped off as illustrated by the dotted lines at 35. The said inner assembly is then sealed into an outer bulb 1 as described in connection with FIG. 10, the said outer bulb being exhausted and gas filled through the exhaust tube 12 and aperture 14'.

It will be evident to those skilled in the art that various changes, omissions and modifications may be made in structural details, materials and assembly steps without departing from the spirit and scope of the invention.

What I claim as new and desire to secure by Letters Patent of the United States is:

The method of manufacturing an electric lamp which comprises arranging an assembly of a single unitary length of an elongated glass envelope having one end closed and the other end open, with a glass exhaust tube extending into the interior of said envelope through the open end thereof, and with a pair of lead-in conductors extending longitudinally into the interior of said envelope beyond said exhaust tube and supporting thereat a filament connected at its ends to the ends of said conductors, heating and softening a zone of said envelope located intermediate its ends and adjacent to the inner end of said exhaust tube, compressing the softened walls of the envelope at said zone to form a single hermetic pinch seal area about the adjacent portions of said conductors and about said exhaust tube while preserving the opening

through the interior of said tube to thereby form a chamber enclosing said filament between the closed end of said envelope and the said hermetic seal area, removing the air from said chamber through said exhaust tube and filling the chamber with a desired atmosphere, reheating a portion of said hermetic seal area adjacent said chamber to soften and collapse the glass thereat to seal off the opening through said exhaust tube, forming an exhaust aperture through the wall of another portion of said seal area in communication with the interior of said exhaust tube, inserting the resulting assembly into the interior of an outer glass bulb through an open neck portion of the bulb, sealing together the peripheries of said bulb neck portion and the outer end of said envelope, evacuating said outer bulb through said exhaust tube and exhaust aperture, and then sealing off said exhaust tube.
